CLOTHES HANGER

Irving Savran, Brooklyn, N. Y., assignor to Amerpro Machine Products, Inc., Brooklyn,
N. Y., a corporation of New York

Application February 10, 1948, Serial No. 144,389

Term of patent 7 years

(Cl. D80—8)

To all whom it may concern:

Be it known that I, Irving Savran, a citizen of the United States, residing at the Borough of Brooklyn, county of Kings, city and State of New York, have invented a new, original, and ornamental Design for a Clothes Hanger, of which the following is a specification, reference being had to the accompanying drawing, forming part thereof.

In the drawing,

Fig. 1 is an elevational view of a clothes hanger embodying my design; and

Fig. 2 is a vertical cross-sectional view, substantially on the line 2—2 of Fig. 1.

I claim:

The ornamental design for a clothes hanger, substantially as shown.
